United States Patent Office

Des. 227,480

Patented June 26, 1973

227,480

INDOOR TELEVISION ANTENNA

John Franzone, 2301 York Road, Lutherville-Timonium, Md. 21093

Continuation-in-part of abandoned design applications Ser. Nos. 149,875, 149,876 and 149,877, all June 3, 1971. This application July 21, 1972, Ser. No. 242,866

Term of patent 14 years

Int. Cl. D14—03

U.S. Cl. D26—14 F

FIG. 1

FIG. 2

FIG. 4

FIG. 6

FIG. 1 is a front perspective view of an indoor television antenna showing my new design;

FIG. 2 is a rear elevation thereof, with portions omitted for ease of illustration;

FIG. 3 is a front perspective view of a modified embodiment of the indoor television antenna disclosed in FIG. 1;

FIG. 4 is a rear elevation thereof, with portions omitted for ease of illustration;

FIG. 5 is a front perspective view of a further modified embodiment of the indoor television antenna disclosed in FIG. 1; and

FIG. 6 is a rear elevation thereof, with portions omitted for ease of illustration.

The inscription shown in broken lines is for illustrative purposes only.

This application is a continuation-in-part of design applications numbered D. 149,875, D. 149,876 and D. 149,877, filed June 3, 1971, now abandoned.

I claim:

The ornamental design for an indoor television antenna, as shown and described.
